UNITED STATES PATENT OFFICE.

WILLIAM J. MCKIBBEN, OF STEUBENVILLE, OHIO.

TRAIN-CONTROLLING MECHANISM.

1,389,063.

Specification of Letters Patent. Patented Aug. 30, 1921.

Application filed June 6, 1921. Serial No. 475,346.

To all whom it may concern:

Be it known that I, WILLIAM J. MCKIBBEN, a citizen of the United States, residing at Steubenville, in the county of Jefferson and State of Ohio, have invented certain new and useful Improvements in Train-Controlling Mechanisms, of which the following is a specification, reference being had to the accompanying drawings.

10 This invention relates to certain improvements in train controlling mechanisms, and it is an object of the invention to provide a mechanism of this general character having novel and improved means whereby a 15 train can be brought to a stop under the influence of a trip member set by a tower man or otherwise operated.

Another object of the invention is to provide a mechanism of this general character 20 including a member carried by a locomotive and releasable by a trip positioned adjacent the trackway, said member when released operating automatically to stop the motive force for the locomotive and which 25 is also adapted, when desired, to cause to operate a signal carried by the locomotive or train.

An additional object of the invention is to provide a novel and improved mechanism 30 of this general character embodying a trip adapted to release a member carried by the train or locomotive to bring the train to a stop and to actuate a signal, said trip being operatively connected with a switch 35 mechanism so that said trip is moved into working position when the switch is open.

The invention consists in the details of construction and in the combination and arrangement of the several parts of my improved train controlling mechanism whereby 40 certain important advantages are attained and the device rendered simpler, less expensive and otherwise more convenient and advantageous for use, as will be herein- 45 after more fully set forth.

The novel features of my invention will hereinafter be definitely claimed.

In order that my invention may be the better understood, I will now proceed to describe the same with reference to the accompanying drawings, wherein:

Figure 1 is a view partly in elevation and partly in section and of a somewhat diagrammatic character illustrating a train controlling mechanism arranged in accordance with an embodiment of my invention,

Fig. 2 is an enlarged fragmentary view illustrating a semaphore arm,

Fig. 3 is an enlarged fragmentary view partly in section and partly in elevation 60 illustrating in detail the means herein disclosed for maintaining the weighted member elevated,

Fig. 4 is a view in rear elevation of the structure as illustrated in Fig. 3,

Fig. 5 is a view in top plan of the structure illustrated in Fig. 3,

Fig. 6 is a sectional view taken substantially on the line 6—6 of Fig. 1,

Fig. 7 is a fragmentary elevational view 70 illustrating certain details of construction as herein disclosed,

Fig. 8 is a fragmentary view in top plan illustrating the connection as herein embodied with a switch rod, and

Fig. 9 is a view partly in elevation and partly in section of the structure as illustrated in Fig. 8.

As disclosed in the accompanying drawings, T denotes a trackway to one side of 80 which is arranged a column C herein disclosed as a pole of the type now generally employed in connection with telegraph lines or the like. Extending from the column C toward the trackway T is a bracket B 85 which serves as a support for the vertically swinging semaphore arm S. This arm is adapted to be operated in a conventional manner from a signal tower or other location.

As herein disclosed, the tail portion of the semaphore arm S has connected therewith an end portion of a flexible member M which extends downwardly and below a guide pulley 1 suitably secured to the column C.

In the present embodiment of my invention, the flexible member M is continued overhead to the tower or other station and the portion of said member between the intermediate poles P is supported by the guide members or pulleys 2 depending from a cable 3 connecting adjacent posts. Upon pull being imposed upon the member M, the semaphore arm S is swung upwardly to substantially a horizontal position and upon release of said member M, the arm S will drop by gravity.

It is also desired that the arm S be swung upwardly into substantially a horizontal or 110 working position in the event a switch is opened, and as herein disclosed, a supple-

mental lever 4 is fixed to the switch lever rod R, and to the outer end portion of said lever 4 is fixed a flexible member M'. This member M' extends downwardly and passes 5 under a guide member or pulley 5 herein disclosed as secured to a tie comprised in the trackway T. From the guide member or pulley 5, the member M is continued through a tube or conduit 6, below a guide pulley 8, 10 and upwardly of an adjacent pole P. This member M' as herein disclosed is also secured, as at 7, to the member M. When the switch lever rod R is thrown over to open the switch, the supplemental lever 4 is simultaneously thrown over resulting in sufficient pull upon the members M' and M to swing the semaphore arm S into extended or working position. The throwing of the semaphore arm S into extended or operative position 15 from the signal tower or other station can be effected independently of the member M'. The member M' may also have secured thereto an additional flexible member F associated with desired guide members or 20 pulleys 9 and this member F leads to the signal tower or other station and is adapted to operate a suitable signal such as a red light or the like within the signal tower or other station to indicate that the switch has 25 been thrown open. When the switch is closed, this signal at the tower or other station is adapted to be automatically operated to show that the switch is in such position.

As the specific construction of this signal 30 at the tower or other station forms in itself no particular part of my present invention, a detailed description thereof is believed to be unnecessary.

E denotes a locomotive. H denotes an 35 standing hollow member arranged at one side of the locomotive and in which is adapted to operate a weighted member W. Secured to the member W is a flexible member 40 10, passing over a suitable guide roller or member 11 and operatively engaged with the throttle lever 12 within the cab of the locomotive so that when the weight is dropped, the lever will be moved into position to shut 45 off the steam. Connected with the member 50 10 is a branch flexible member 14 suitably guided by the pulley 15 and which is operatively engaged with the valve of the whistle 16 so that as the weight drops, the whistle is caused to sound giving audible signal and 55 particularly to the tower man or person at a similar station that the mechanism has operated, and to the engine man and the remainder of the train crew. This is of particular advantage in the event the train should pass 60 into a closed block or in the event that a switch in advance of the train has been moved into open position. The weighted member W is maintained in a raised position through the medium of a trap door 17 65 hingedly mounted within the hollow member

H. The trap door 17 is provided with an arm 18 substantially coplanar therewith and which extends exteriorly of the member M through a longitudinally disposed slot 19, said slot 19 being of such length to permit 70 the extension or arm 18 to pass therethrough when the door 17 drops.

When the trap door 17 is in a raised or elevated position to support the weighted member W, a lug or finger 20 is engaged 75 below the extension or arm 18 to maintain the door 17 raised. This lug or finger 20 is carried by the lower end portion of a plate or strip 21 fixed to the lower end portion of a vertically disposed arm 22. This arm 22 80 is pivotally supported intermediate its length by the member H as indicated at 23 and whereby said arm or bar is capable of swinging movement. The arm or bar 22 is 85 of a length to extend above the member H.

Connecting the member H and the arm or bar 22 at a point below the pivotal mounting 23, is a retractile member or spring 24 which operates to constantly urge the lower end portion of said arm or bar 22 toward the arm 90 or extension 18 so that the lug or finger 20 is maintained in desired position below the extension or arm 18.

The top of the member H is closed by a 95 plate 25 which extends upwardly from the member H and laterally of the locomotive E. Superimposed upon the plate 25 is a lever or elongated arm 26 pivotally supported, as at 27, intermediate its length to the plate 25. The inner end portion of the lever or arm 26 100 overlaps the upper or extended end portion of the member or bar 22 while the opposite end portion of the lever or arm 26 extends beyond the outer end of the plate 25 a distance to contact with the semaphore arm S 105 when in extended or working position. The inner end portion of the lever or arm 26 is maintained in contact with the upper or extended portion of the member or bar 22 by a retractile member 28, herein disclosed as a 110 coil spring, having one end portion secured to the lever or arm 26 and its opposite end portion secured to the plate 25.

As the train advances with the semaphore arm in extended or working position, the 115 outer end portion of the lever or arm 26 will contact with the outer end portion of the semaphore arm S resulting in the inner end portion of the lever or arm 26 rocking or swinging the member or bar 22 in a direction 120 to disengage the lug or finger 20 from below the extension or arm 18 of the door 17, whereupon the weighted member W drops within the standard H resulting in the throttle lever 12 being moved in a position to cut 125 off the steam and also resulting in the sounding of the whistle 16.

From the foregoing description it is thought to be obvious that a train controlling mechanism constructed in accordance 130

with my invention is particularly well adapted for use by reason of the convenience and facility with which it may be assembled and operated, and it will also be obvious that 5 my invention is susceptible of some change and modification without departing from the principles and spirit thereof and for this reason I do not wish to be understood as limiting myself to the precise arrangement 10 and formation of the several parts herein shown in carrying out my invention in practice except as hereinafter claimed.

I claim:

1. A train controlling apparatus comprising 15 in combination, an upstanding hollow standard carried by the locomotive, a trap door therein, means for holding the trap door in a raised position, a weighted member adapted to rest upon the trap door and to drop 20 downwardly of the hollow standard when the trap door is released, a locomotive including a lever for controlling the motive force therefor, said weighted member being operatively connected with the lever, said 25 weighted member when dropped moving the lever to a position to cut off the motive force, and means positioned adjacent the path of travel of the locomotive for releasing the holding means for the trap door.

30 2. A train controlling mechanism comprising in combination, a locomotive provided with a lever for controlling the motive force for the locomotive, a trap door carried by the locomotive, a swinging arm coacting 35 with the trap door for holding the same in raised position, a weighted member adapted to rest upon the trap door, an operative connection between the weighted member and the lever, said weighted member upon 40 release of the trap door operating to move the lever into a position to cut off the motive force, a movable member coacting with the trap door for holding the same in raised position, a second swinging arm carried by 45 the locomotive and extending laterally beyond the side thereof, and means positioned adjacent the path of travel of the locomotive for contact with the swinging arm to cause 50 said swinging arm to engage the movable member to move the movable member in a direction to release the trap door.

55 3. A train controlling mechanism comprising in combination, a locomotive provided with a lever for controlling the motive force for the locomotive, a trap door carried by the locomotive, a swinging arm coacting 60 with the trap door for holding the same in raised position, a weighted member adapted to rest upon the trap door, an operative connection between the weighted member and the lever, said weighted member upon release 65 of the trap door operating to move the lever into a position to cut off the motive force, a movable member coacting with the trap door

for holding the same in raised position, a 65 second swinging arm carried by the locomotive and extending laterally beyond the side thereof, means positioned adjacent the path of travel of the locomotive for contact with the swinging arm to cause said swinging 70 arm to engage the movable member to move the movable member in a direction to release the trap door, and automatic means for normally maintaining the movable member in 75 operative engagement with the trap door.

4. A train controlling mechanism comprising in combination, a locomotive provided with a lever for controlling the motive force for the locomotive, a trap door carried by the locomotive, a swinging arm coacting 80 with the trap door for holding the same in raised position, a weighted member adapted to rest upon the trap door, an operative connection between the weighted member and the lever, said weighted member upon release of the trap door operating to move the lever into a position to cut off the motive 85 force, a movable member coacting with the trap door for holding the same in raised position, a second swinging arm carried by 90 the locomotive and extending laterally beyond the side thereof, means positioned adjacent the path of travel of the locomotive for contact with the swinging arm to cause said swinging arm to engage the movable 95 member to move the movable member in a direction to release the trap door, and automatic means for normally maintaining the swinging arm in contact with the movable member.

100 5. A train controlling mechanism comprising in combination, a locomotive provided with a lever for controlling the motive force for the locomotive, a trap door carried by the locomotive, a swinging arm coacting 105 with the trap door for holding the same in raised position, a weighted member adapted to rest upon the trap door, an operative connection between the weighted member and the lever, said weighted member upon release of the trap door operating to move the lever into a position to cut off the motive 110 force, a movable member coacting with the trap door for holding the same in raised position, a second swinging arm carried by 115 the locomotive and extending laterally beyond the side thereof, and means positioned adjacent the path of travel of the locomotive for contact with the swinging arm to cause said swinging arm to engage the movable 120 member to move the movable member in a direction to release the trap door, the means adjacent the path of travel of the locomotive being movable into and out of operative position.

125 In testimony whereof I hereunto affix my signature.

WILLIAM J. McKIBBEN.
